Fig. 1

Fig. 2

FIGURE 1 is a top perspective view of an ash tray showing my new design; and

FIGURE 2 is a side elevation view of the ash tray of FIGURE 1 showing one side receptacle projecting toward the viewer and another in profile, the opposite side being substantially a mirror image thereof.

This is a division of my copending application, Ser. No. D. 13,108, filed Aug. 12, 1968.

I claim:

The ornamental design for an ash tray, as shown and described.
